UNITED STATES PATENT OFFICE.

RICHARD BENJAMIN PAINTON, OF WILLIAMSPORT, PENNSYLVANIA, AS-
SIGNOR, BY DIRECT AND MESNE ASSIGNMENTS, OF SEVEN-SIXTEENTHS
TO WILLIAM H. BAINBRIDGE, OF LONDON, ENGLAND, AND D. CLARENCE
WILLOUGHBY, OF NEW YORK, N. Y.

ELECTRICALLY-OPERATED RUDDER-CONTROLLING MECHANISM.

SPECIFICATION forming part of Letters Patent No. 624,531, dated May 9, 1899.

Application filed September 13, 1897. Serial No. 651,527. (No model.)

To all whom it may concern:

Be it known that I, RICHARD BENJAMIN PAINTON, a citizen of the United States, residing at Williamsport, in the county of Lycoming and State of Pennsylvania, have invented a new and useful Electrical Rudder-Controlling Mechanism, of which the following is a specification.

This invention relates to rudder-controlling mechanism for ships; and it has for its object to provide a mechanism of this character controlled entirely by electricity and especially designed for use in combination with an electrical system of marine propulsion of the character disclosed in my pending application, filed May 7, 1897, Serial No. 635,578, in order that every movement of the ship can be controlled from a convenient point by the manipulation of a suitable electrical switchboard.

To this end the invention primarily contemplates simple and improved means of applying electrical power to the rudders of ships, whereby space and weight may be greatly economized, and by a suitable system of wiring to suitable switchboards at various points through the ship the rudder may be accurately and quickly controlled.

For a full understanding of the merits and advantages of the invention reference is to be had to the accompanying drawings and the following description.

The improvement is susceptible of various changes in the form, proportion, and the minor details of construction without departing from the principle or sacrificing any of the advantages thereof, and to a full disclosure of the invention an adaptation thereof is shown in the accompanying drawings, in which—

Figure 1 is a diagrammatic sectional view of the stern of the ship or vessel, showing the rudder fitted with the controlling mechanism contemplated by this invention and also showing in diagram a switchboard-circuit for reversing the direction of the current in the leads for the electric motor. Fig. 2 is a sectional view on the line 2 2 of Fig. 1.

Referring to the accompanying drawings, the numeral 1 designates the hull of a ship or vessel, at the stern of which is arranged the

rudder 2, hinged in position in the usual manner and having extended upward therefrom into the body of the vessel the vertical rudder-shaft 3.

In the present invention the vertical rudder-shaft 3 may be joined to the rudder 2 in any suitable manner to provide for the necessary swing or movement of the latter, but is forged on the lines of an armature-shaft of an electric motor, so as to form the armature-shaft of an electric controlling-motor 4. The electric controlling-motor 4 is supported in position within the stern of the hull in any suitable manner and is constructed essentially the same as ordinary electric motors, having the usual fields 5 and the rotating armature 6 working between the fields. However, in adapting the motor for use in connection with the vertical shaft of the rudder the said motor must be of a reversible type and especially built to suit the particular space and shafting designed for use in connection therewith, and the motor must also be of a type that will run or turn slowly in either direction. To provide for adapting the controlling-motor 4 to the vertical shaft 3, the armature 6 is wound directly on the said shaft, so that the latter will not only form the rudder-shaft, but also the armature-shaft as well, thereby obviating the slightest degree of lost motion and rendering the rudder sensitive to the slightest energization of the motor.

As already explained, the electric motor 4 may be of any approved type, but must be specially wound for the purpose, so that the armature will move and rotate at a slow speed in either direction. The only requirements, therefore, of the motor are that the same be of a reversible type and that the winding be of such a character as to provide for the slow rotation or movement of the armature. Relative to the switchboard herein referred to I do not claim any special design of switchboard or any particular arrangement thereof, but only contemplate using any suitable switchboard which will provide for reversing the direction of the current through the electric motor and for cutting the current off, and for the purposes of illustration a switchboard-circuit is shown

in Fig. 1 of the drawings. In this figure of the drawings the number 20 designates an ordinary dynamo or electrical generator which is arranged at any point within the ship or vessel, and which dynamo or generator has included in the circuit thereof an ordinary reversing - switchboard 21. The reversing switchboard 21 is of a common construction and has suitable wire connections with the fields and brushes of the electric motor 4, so that by shifting the position of the switch-arms 22, which are coupled together and move in unison in the usual manner, the current will be reversed through the leads of the electric motor, as plainly illustrated in Fig. 1 of the drawings.

The reversing-switchboard 21 is designed to be arranged in the captain's chart-room or at any other suitable place within the ship, so that by a movement of the switch arms or levers 22 in either direction the armature of the motor can be caused to rotate in the proper direction. When the rudder of the ship has been turned to the desired degree, the switchboard is manipulated to immediately reverse the current through the motor, so as to instantly check the further movement of the rudder, and then the current is cut off entirely, after which the rudder will be held in its adjusted position by the friction - arresting device, which will now be described.

The upper end of the combined rudder and armature shaft 3 may be conveniently fitted in a brace-bearing 7, below which said shaft 3 has fitted thereon a horizontal spur-gear 8, spaced a slight distance from and arranged concentrically with a stationary segmental rack 9, having teeth 10 on its inner edge and bolted or otherwise secured in a fixed position within the stern of the vessel adjacent to the spur-gear 8. In connection with the spur-gear 8 and the concentric rack 9 there is employed a traveling pinion 11, interposed between said gear and rack and meshing with the teeth thereof.

The traveling pinion 11 is loosely journaled on an upwardly-disposed spindle-pin 12, upturned from one end of a horizontal brake-arm 13, the other end of which brake-arm has fitted thereto a brake-band 14, frictionally embracing the shaft 3, immediately below the spur-gear 8, and providing means for checking any tendency of the shaft 3 to turn except under the influence of the electric motor, while at the same time serving to hold the arm 13 in such a position that the traveling pinion 11 will maintain its proper relation to the gear 8 and rack 9 as it rolls or travels in the space therebetween. It will also be observed that the stationary rack 9, in connection with the pinion 11 and the spur-gear 8, provides simple and positive means for effectually restraining the motion of the brake-arm 13, while at the same time not interfering with the swinging movement of the arm to maintain the proper relative position of the pinion 11 to the spur-gear and said rack, irrespective of

the angle or degree to which the rudder may be turned.

When the electric motor is energized to turn the rudder-shaft 3, the spur-gear 8 and the brake-arm 13 will necessarily turn with such shaft, thereby causing the pinion 11 to travel against the rack 9 toward either end thereof, according to the direction of rotation of the rudder-shaft, and by reason of the band 14 frictionally gripping the shaft 3 the said band, in connection with the gears 8 and 11 and the rack 9, will constitute an arresting device for the rudder to hold the same in its adjusted position and prevent it from being thrown back in line with the keel of the ship by the action of the propellers at either side of the same, especially when the propellers are arranged as shown in my pending application herein referred to. In other words, any tendency of the shaft 3 to turn back and carry the brake-arm 13 therewith would be withstood by the interlocking-gears which hold the swinging end of the brake-arm, while the other end thereof frictionally grips the rudder-shaft.

While I have shown and described a particular arrangement of the controlling-motor and the arresting device for the rudder, it will be understood that these or other parts of the controlling mechanism may be modified and arranged according to the particular character and size of the space designed to receive the same without in any way departing from the spirit of this invention, and it will also be understood that any well-known system of electrical distribution and switchboards may be employed for the purpose of energizing and reversing the motor without affecting the essential feature of the invention, which is the idea of applying an electric motor directly to the vertical shaft of a rudder, as I am not aware that such application and arrangement of an electric motor has heretofore been resorted to.

Having thus described the invention, what is claimed as new, and desired to be secured by Letters Patent, is—

1. In an electrical rudder-controlling mechanism, the combination with the vertical rudder-shaft, of a reversible electric controlling motor having its armature coupled to the shaft, a horizontal spur-gear fitted on the shaft above the motor, a stationary segmental rack arranged adjacent to and concentric with said spur-gear, a swinging brake-arm having a friction - brake - band connection at one end with the rudder-shaft, and a pinion loosely supported on the swinging end of said arm and traveling between and in mesh with the spur-gear and segmental rack, substantially as set forth.

2. In an electrical rudder-controlling mechanism, the combination with the vertical shaft of the rudder, of a reversible electric motor having its armature wound directly on the rudder-shaft, an arresting device having a brake member engaging the rudder-shaft, means for transferring motion to the brake

member from the rudder-shaft, and means for restraining the motion of said brake member, substantially as set forth.

3. In an electrical rudder-controlling mechanism, the combination with the rudder-shaft, of a reversible electric motor having operative connection with the shaft, an arresting device having a brake member engaging the rudder-shaft, and a gear connection with said 10 brake member to provide for restraining the motion thereof, substantially as set forth.

4. In an electrical rudder-controlling mechanism, the combination with the rudder-shaft, of a reversible electric motor having operative connection with the shaft, a swinging 15 brake-arm frictionally engaging with the shaft, and means for restraining the movement of the brake-arm with the rudder-shaft, substantially as set forth.

20 5. In an electrical rudder-controlling mechanism, the combination with the rudder-shaft, of a reversible electric motor having operative connection with the shaft, an arresting device having a movable brake member 25 engaging with the rudder-shaft, and a gearing-train for restraining the motion of the brake member, substantially as set forth.

6. In an electrical rudder-controlling mechanism, the combination with the rudder-shaft, 30 of a reversible electric motor having operative connection with the shaft, a swinging

brake-arm frictionally engaging with the shaft, and gearing for retarding the motion of the brake-arm, substantially as set forth.

7. In an electrical rudder-controlling mechanism, the combination with the rudder-shaft, of a reversible electric motor having operative connection with the shaft, an arresting device having a movable brake member frictionally engaging the rudder-shaft, and a 40 train of restraining-gears, one of the gears being fitted to the rudder-shaft, and another to a fixed part of the vessel, substantially as set forth.

8. An electrical rudder-controlling mechanism, the combination with the rudder-shaft, of a reversible electric motor having operative connection with the shaft, a brake having its movable member engaging with the shaft, a stationary segmental rack fitted to 50 a fixed part of the vessel, a spur-gear fitted to the rudder-shaft, and a pinion interposed between the spur-gear and rack and supported by the movable brake member, substantially as set forth.

In testimony that I claim the foregoing as my own I have hereto affixed my signature in the presence of two witnesses.

RICHARD BENJAMIN PAINTON.
